Attorney,

UNITED STATES PATENT OFFICE.

EDWIN B. EVANS, OF PROVIDENCE, RHODE ISLAND, ASSIGNOR TO WAITE, EVANS COMPANY, A CORPORATION OF RHODE ISLAND.

DESIGN FOR A ROSARY.

Application filed March 27, 1923. Serial No. 5,615. Term of patent 14 years.

To all whom it may concern:

Be it known that I, EDWIN B. EVANS, a citizen of the United States, residing at Providence, in the county of Providence and State of Rhode Island, have invented a certain new, original, and ornamental Design for a Rosary, of which the following is a specification, reference being had to the accompanying drawings, forming part thereof.

The drawing is a front elevation of a rosary embodying my design.

The chain comprises disks or medallions, indicative of different typical scenes in the life of Christ, connected by links having a larger and a smaller bead contrasting with the disks.

I claim:

The ornamental design for a rosary, as shown.

EDWIN B. EVANS.
